(57) **CLAIM**

The ornamental design for a watch band, as shown and described.

DESCRIPTION

FIG. 1 is a top perspective view of a watch band embodying my new design;

FIG. 2 is a bottom perspective view thereof;

FIG. 3 is a top plan view thereof;

FIG. 4 is a bottom plan view thereof;

FIG. 5 is a left-side elevational view thereof;

FIG. 6 is a right-side elevational view thereof;

FIG. 7 is a front elevational view thereof;

FIG. 8 is a back elevational view thereof;

FIG. 9 is a top perspective view thereof with a watch element attached to the watch band; and,

FIG. 10 is a bottom perspective view of the watch band in a buckled configuration with the watch element attached to the watch band.

The broken lines in FIGS. 9 and 10 forming the watch element, which is a separate environmental structure from the watch band, form no part of the claimed design. The illustrated stitching in the Figures forms part of the claimed design.
